UNITED STATES PATENT OFFICE.

LOUIS P. BLIEMEISTER, OF BUFFALO, NEW YORK, ASSIGNOR OF ONE-HALF TO WILLIAM R. JESEPH, OF BUFFALO, NEW YORK.

JUNCTION-BOX FOR ELECTRIC WIRES.

No. 876,619.

Specification of Letters Patent.

Patented Jan. 14, 1908.

Application filed July 20, 1906. Serial No. 327,058.

To all whom it may concern:

Be it known that I, LOUIS P. BLIEMEISTER, a citizen of the United States, residing at Buffalo, in the county of Erie and State of New York, have invented certain new and useful Improvements in Junction-Boxes for Electric Wires, of which the following is a specification.

This invention relates to junction-boxes for electric wires.

In the wiring of buildings or other structures, several independent circuits are employed, and these circuits are connected with the main-conductors through the intervention of fuse-plugs. The connections are generally made within a junction-box, or what is sometimes termed a "distribution-box". The fire underwriter's rules limit the number of lamps on any circuit, and when a four circuit junction-box is used and it is desired to install additional lamps above the number permitted on the four circuits, an additional junction-box must be used, or the old box replaced with a larger one in which provision is made for additional circuits. This change involves considerable expense and labor, and many sizes of junction-boxes must be carried in stock to meet the various requirements. These junction-boxes are usually rectangular in form and provided with a cover; the ends having openings for the main conductors, and the sides having openings for the independent circuit-wires. The usual way of connecting the independent circuit-wires with the main-conductors is by means of fuse-blocks secured to the rear-wall of the junction-box; the latter being embedded in a wall of a building.

The primary object of my invention is the production of an expansible junction-box to permit of enlarging upon the number of independent circuits in use at any time desired.

Another object is to construct the body of the box in two telescoping parts so that the openings for the independent circuit-wires in said two parts register when the box is contracted, and when expanded to enlarge upon the number of independent circuits, the end openings in the sides of each part of the box are moved out of registration with the openings in the other part of the box.

Still further objects are, the production of an expansible junction-box comprising an expansible body and an expansible cover

hinged to the body and connected with the latter so that on expanding or contracting the body, the cover is likewise expanded or contracted; to provide a junction-box having the free edge of the side and end walls of the body thereof bent to the form of a channel opening toward the rear of the box and the edges of its cover also bent to the form of a channel opening against the outer surface of the sides and ends of the body; to provide a box of simple and inexpensive construction; and to otherwise improve on junction-boxes now in use.

To these ends the invention consists in the construction, arrangement, and combination of parts to be hereinafter described and particularly pointed out in the appended claims.

In the drawings,—Figure 1 is a front elevation of a junction-box constructed according to my invention, the cover of the same being partly open. Fig. 2 is a perspective view of the body of the box in contracted condition. Fig. 3 is a perspective view of the body of the box partly expanded. Fig. 4 is a perspective view of one part or section of the box with the sides and end thereof formed to accurate shape and about to be bent into proper position for connection at the corners. Fig. 5 is a detached perspective view of the cover. Fig. 6 is a transverse section through the box, the cover being closed. Fig. 7 is a horizontal section taken on line z—z, Fig. 6.

Referring now to the drawings in detail, corresponding numerals of reference refer to corresponding parts in the several figures.

The reference numeral 1 designates the body of the junction-box and 2 the cover thereof. The body of the box comprises a rear wall 3, side walls 4 and end walls 5. Fuse blocks 6 are secured to the rear wall of the box and electrically connected to the said blocks are the main conductors 7 which pass through the box and through conduits 8 whose ends are threaded and extend through openings 9 in the end walls of the box; said conduits having nuts 10 threaded thereon which bear against opposite sides of the end walls and serve to secure the conduits to said walls.

The body of the box consists of two parts or sections 11 and 12; section 11 being of less depth and width than section 12 so as to fit snugly within the same. Each section comprises a rear wall 13, a single end wall 14

105

110

and side walls 15; said end wall and side walls having their outer free edges bent to channel-shape, as at 16; the channel of section 11 fitting snugly within the channel of 5 section 12. In this manner a stiff and durable construction is obtained, which assures free action in expanding or contracting the box.

Each of the sections 11, 12, is constructed 10 of a single sheet of metal, bent to form the end-wall 14 and the side-walls 15; the latter having each an inwardly directed extension 17 lying against the inner side of the end wall, and a cut-away portion 18 at the ends 15 thereof forming the corner of the box, while the ends of the end-wall have extensions 19 bent against the outer sides of the side-walls and being of sufficient width to cover the cut-away portions 18, and outstanding securing- 20 ears 20 formed integrally with extensions 19, and originally filling the space formed by the cut-away portions of the side-walls.

The rear wall of each section has screw-holes 21 and the side walls have openings 22 25 into which are secured conduits 23 having their threaded inner ends passing through said openings and nuts 24 applied thereto which bear on opposite sides of the side walls and serve to secure said conduits to the box. 30 Independent circuit-wires 25 pass through said conduits and have their inner terminals secured to the fuse-blocks. The connection of the independent circuit-wires to the main conductors is made through the intervention 35 of the fuse-blocks which is common to those skilled in the art, and requires no detail illustration or further description.

When the box is contracted, as shown in Fig. 2, the independent circuit-wire openings 40 22 register, and when in this condition the conduits 23 pass through two thicknesses of metal. The screw-holes 21 formed in the rear wall of each section also register, and passed through the same are the securing- 45 screws 26 by means of which the fuse-blocks are secured within the box.

As shown in Fig. 3, the box is expanded to increase the number of independent circuits, and when in this position, the openings 50 55 in the side walls of the sections nearest the corners thereof are moved out of registration, while the two remaining openings of each section are brought into registration with different openings of the other section. The box may be further expanded to increase the 60 number of side openings. The cover 2 is formed of two sections 27, each having its marginal portions at the sides and one end bent upon itself to form channels 28 which 65 open inward against the sides and ends of the body of the box, as shown in Fig. 6. One section of the cover is of slightly smaller width than the other and the channel is of less width than that of the other section, so as to fit snugly but slidably within said other

section. The wide section of the cover is hinged to the outer or large section of the body, as at 29, while the narrow section of the cover is hinged to the inner or small section of the body, as at 30. Therefore, when 70 expanding the body of the box, the cover is also expanded, each section of the cover retaining its hinged relation with the corresponding section of the body.

Many changes in construction and minor 75 details of arrangement of the several parts may be resorted to without departing from the spirit of my invention or sacrificing any of the advantages thereof; it being understood that the claims appended hereto are 80 to be given the broadest construction permissible by the prior art.

Having thus described my invention, what I claim is,—

1. A junction-box for electric-wires 85 constructed of metal and comprising a body-portion having the upper edge of its side and end walls bent inward and rearward to form a rearwardly opening channel, and a cover having its marginal portion bent rearward 90 and inward to form an inwardly opening channel.

2. A junction-box for electric-wires consisting of telescoping-sections having one or 95 more walls thereof provided with openings for the circuit wires, said sections being movable with reference to each other to bring part or all of the openings of both sections into registration or to move the same out of registration.

3. A junction-box for electric-wires consisting of a body-portion having telescoping sections provided in the side walls thereof with openings and having in the rear walls thereof screw-holes, said sections being movable with reference to each other to bring all or part of said openings and screw-holes of one section into registration with the openings and screw-holes of the other section. 105

4. A junction-box for electric-wires comprising a telescoping-body portion and a telescoping-cover, said body-portion having openings for the introduction of circuit wires. 110

5. A junction-box for electric-wires comprising a telescoping-body having two sections fitting one within the other, each section having openings for the introduction of wires, and the openings of one section being brought into or moved out of registration with the openings in the other section when 115 contracting or expanding the box, and a telescoping cover having two sections, each section of the cover being hinged to the corresponding section of the body. 120

6. A junction-box formed of two sections 125 fitting one within the other to permit of contracting or expanding the box, each section comprising a rear wall, a single end wall having inwardly directed extensions lying against outer sides of the side walls, and side walls 130

having each an inwardly directed extension lying against the inner side of the end wall, the side walls of said sections having openings for the introduction of circuit-wires, 5 all or part of the openings of one section being moved into or out of registration with the openings of the other section.

7. A junction-box formed of two telescoping sections, each comprising a rear wall, an 10 end wall having its upper edge bent inward and rearward to form rearwardly opening channels, side walls having their upper edges also bent inward and rearward to form rearwardly opening channels fitting one within 15 the other; the side walls of each section having openings for the introduction of circuit-wires, all or part of the openings of one section being moved into or out of registration with the openings of the other section.

20 8. A box of the kind described, comprising two open-ended members having open tops, these members being arranged to telescope, means for securing the members to a struc-

ture and each member having alined perforations, the extended box being adapted to 25 hold two switches and the perforations forming passages for the conduits of each switch, and the perforations all being in axial alinement when the members are slid together to hold one switch, passage thereby being 30 furnished for one pair of conduits.

9. A box of the kind described, comprising a pair of open-ended members arranged to telescope one within the other, and having a perforation in each of the opposed walls of 35 the members, the perforations being arranged to be in axial alinement when the members are slid together.

In testimony whereof, I have affixed my signature in the presence of two subscribing 40 witnesses.

LOUIS P. BLIEMEISTER.
